UNITED STATES PATENT OFFICE.

DENIS HOWARD, OF BINGHAMTON, NEW YORK.

RECEIVER-HOOK FOR TELEPHONES.

No. 831,001.

Specification of Letters Patent.

Patented Sept. 11, 1906.

Application filed January 16, 1906. Serial No. 296,417.

To all whom it may concern:

Be it known that I, DENIS HOWARD, a citizen of the United States, residing at Binghamton, in the county of Broome and State 5 of New York, have invented a new and useful Receiver-Hook for Telephones, of which the following is a specification.

This invention relates to telephones, and more particularly to improved mechanism 10 for automatically transmitting identifying or selective signaling impulses.

The object of the invention is to provide means for signaling the central office when any particular subscriber is using the telephone and means for notifying said subscriber of any intruder on the line.

A further object of the invention is to provide a switch-hook having a plurality of circuit make and break members for indicating 20 the number of the local station as the receiver is removed from or placed upon the hook.

A still further object is to form the switch-hook with interchangeable contact members movable by gravity to operative position for 25 transmitting the signaling impulses.

With these and other objects in view the present invention consists in the construction and novel combination and arrangement of parts hereinafter fully described, and illustrated in the accompanying drawings, it being understood that changes in form, proportions, and general assemblage of parts may be resorted to within the scope of the appended 30 claims.

In the accompanying drawings, forming a part of this specification, Figure 1 is a vertical sectional view of a portion of a call-box, showing my improved switch-hook applied thereto. Fig. 2 is a perspective view of the 40 switch-hook detached. Fig. 3 is a diagrammatical view showing several subscribers' stations. Fig. 4 is a top plan view of a portion of a hook, illustrating a modified form of the invention.

Similar numerals of reference indicate corresponding parts in all of the figures of the drawings.

The improved hook is especially designed for use in connection with telephones on 50 party-lines, and by way of illustration several subscribers' stations (indicated, respectively, at A, B, C, and D) are shown in diagram, each station having a telephone provided with my improved switch-hook 5.

The hook 5 is preferably formed of a flat 55 bar of metal, one end of which is bifurcated and twisted at right angles to the body portion to form a support for the receiver 6, the opposite end of the bar being offset at 7 to form a seat for a segmental contact-plate 8. 60 The intermediate portion of the hook is provided with an aperture 9, adapted to receive a pivot-pin 10, which passes through aligned openings in a supporting-bracket 11, the latter being secured in any suitable manner to 65 the interior walls of the call-box or casing 12.

The plates 8 are interchangeable and detachably secured to the offset portions of hooks by bolts or similar fastening devices 13, each plate being provided at its curved 70 edge 14 with one or more laterally-projecting lugs or contact members 15, adapted to successively engage a spring-contact member 16 when the receiver is removed from or placed upon the hook, and thereby send a series of 75 selective impulses over the main line 17 to the central office.

The number of impulses sent over the line will of course be governed by the number of contacts 15 on the plates 8, the plates at one 80 station having a different number of contacts from the plate of an adjacent station, so as to indicate a different signal for each subscriber.

The plates 8 in addition to carrying the 85 contact members also form counterweights, so that when the receiver is removed from the hook the inner end thereof will drop by gravity and cause the contacts to wipe the members 16, and thus close the circuit. 90

As a means for limiting the downward movement of the weighted end of the hook a stop 17 is secured to the interior walls of the call-box. The stop 17 is provided with a slot 18, whereby said stop may be adjusted vertically to regulate the throw of the hook, said stop being locked in adjusted position by tightening the clamping-screw 19.

If desired, a spring 20 may also be disposed above the hook to assist in moving the latter 100 to operative position.

From the foregoing description it will be understood that when the receiver is removed from the hook at any particular subscriber's station the weighted end thereof will drop by 105 gravity, and thus successively make and break the circuit according to the number of contacts on the plate 8, and when the re-

ceiver is replaced upon the hook the return movement of the latter will cause a similar set of impulses to be sent over the line.

It will also be understood that should any 5 particular subscriber endeavor to intrude or listen to another subscriber the subscriber using the line will be notified of the fact by the signal.

In Fig. 4 of the drawings there is illustrated 10 a modified form of receiver-hook in which the bar 5' is straight or uninterrupted, the plate 8' being detachably secured thereto in the manner before described.

Having thus described the invention, what 15 is claimed is—

1. A telephone-hook having one end thereof provided with a detachable contact-plate carrying a plurality of make and break members for indicating the local station as the receiver is removed from or placed upon the 20

hook, and an adjustable stop disposed beneath the hook for limiting the downward movement thereof.

2. A telephone switch-hook comprising a bar having one end thereof bifurcated and 25 twisted to form a support for a receiver and its opposite end provided with an offset portion, and a plate detachably secured to the bar and seated in the offset portion of the latter, said plate having one longitudinal edge 30 thereof provided with a plurality of spaced laterally-extending lugs forming contacts.

In testimony that I claim the foregoing as my own I have hereto affixed my signature in the presence of two witnesses.

DENIS HOWARD.
